UNITED STATES PATENT OFFICE.

EDWARD BRUNHOFF, OF CINCINNATI, OHIO, ASSIGNOR TO THE BRUNHOFF MANUFACTURING COMPANY, OF CINCINNATI, OHIO, A CORPORATION OF OHIO.

DISPLAY AND VENDING APPARATUS.

Application filed August 17, 1922. Serial No. 582,505.

To all whom it may concern:

Be it known that I, EDWARD BRUNHOFF, a citizen of the United States, residing at Cincinnati, in the county of Hamilton and State of Ohio, have invented certain new and useful Improvements in Display and Vending Apparatus, of which the following is a specification.

My invention relates to improvements in display and vending apparatus. One of its objects is to provide improved apparatus to support the original packages upon a counter or similar support in an inclined position for vending purposes. Another object is to provide such apparatus adapted to be detachably applied to a succession of original packages. Another object is to provide such apparatus to be detachably interposed between the mouth of the original packages and their lids, after the lids of the original packages have been removed with provision for a more ready access to the contents of the original package than by removing and replacing its lid. Another object is to provide an improved loop or band and a foot or support with a lid hinged thereto to be detachably applied to an original package after its lid has been removed to support an original package in an inclined position suited to displaying its contents, to protect the contents from dust or injury and to afford ready access to said contents. My invention also comprises certain details of form, and relation of component members, all of which will be fully set forth in the description of the accompanying drawings, in which:

Fig. 1, is a central vertical section through an original package in position to vend its contents, with my improvements applied thereto, taken on line 1—1 of Fig. 2.

Fig. 2 is a front elevation of Fig. 1.

Fig. 3, is a detail of one of the padded ends of the supporting member.

Fig. 4, is a perspective view of one of the original packages before its lid has been removed.

Fig. 5, is a perspective view of my improved apparatus before it is applied to an original package.

The accompanying drawings illustrate the preferred embodiment of my invention in which 15 represents a sheet metal band or loop to be applied to the mouth of an original package 16, as for instance a sheet

metal cigar can or box, after the lid 17 of the original package has been removed. The band 15 is preferably applied to telescope over the mouth of the original package at and in place of the lid 17. A support or foot 18 is preferably attached rigidly to the band 15 and when the band has been attached to an original package and the package 16 inclined as shown in Fig. 1, the support 18 and the edge 19 of the bottom of the original package serve as supports to firmly retain the original package in an inclined position as shown in Figs. 1 and 2; favorable to a display or inspection of the goods or contents of the original package through its open mouth by a prospective purchaser. The support 18 also affords a prominent space 20 suited to the display of advertising matter calculated to assist in vending the goods.

An annular band 21 having a cylindrical section 22 and a flaring, bell-shaped or conical section 23 is hinged to the band 15 by means of hinge members 24 and 25 and a hinge axle 26. A metal tongue 27 projects upwardly from the hinge member 25 to provide a finger hold to enable the band 21 to be lifted or turned upon its hinge axle. The cylindrical section 22 of the band 21 is of substantially the same diameter as the mouth of the original package 16 so that the lid 17 which fits snugly and telescopically over the mouth of the original package, when removed from the original package, may be snugly and telescopically fitted over the section 22 of the band 21 to close one end of said band and form, with said band, a readily removable cap to close the mouth of the original package, and which may be readily lifted to permit inspection and access to the contents of the original package while at the same time affording a protection against dust, etc.; a means to retain moisture, and a means to prominently display such trade-mark or advertising matter as may be displayed upon the top or outer face of the lid 17. The flaring section 23 of the band 21 provides for a relatively close joint or fit of the band 21 upon the edge of the band 15, and at the same time a joint which is not liable to catch or accidentally prevent lifting of the band 21 away from the band 15 to give access to the contents of the original package.

In order to avoid injury to glass or varnished surfaces on which the original pack-

ages may be mounted for display I preferably provide sheet metal projections 30 and 31 at the lower extremities of the support 18, over which projections are drawn 5 short sections of rubber tubing or similar annular bands of soft yielding material 32 to form yielding pads at the points of contact between the support 18 and any object upon which it may be supported.

10 An outwardly projecting annular bead 33 may be provided near the mouth of the original package to limit the telescopic movement of the lid 17 or band 15 over the mouth of the original package. An inwardly turned annular bead 34 is preferably provided in the band 15 to limit the extent to which said band 15 will telescope over the mouth of the original package. The raw edges at each end of the band 15 are 15 preferably turned inwardly to provide smooth finished edges for the band 15. The raw edges at each end of the band 21 are also preferably turned inwardly for a like purpose. The bands 15 and 21 and the support 18 are adapted to be successively detached from one original package and applied to another as the contents of each package becomes exhausted.

The apparatus herein shown and described 20 is capable of considerable modification within the scope of the claims without departing from the spirit of my invention.

What I claim is:

1. A display and vending apparatus comprising in combination with a sheet-metal original package, a sheet metal member adapted to telescopically, detachably engage the mouth of said original package in place of its original sheet metal lid, a supporting member carried by said sheet metal member and adapted to support said original package and sheet metal member in an inclined position and a lid hinged to the edge of said sheet metal member adapted to 45 open and close the mouth of said original package.

2. A display and vending apparatus comprising in combination with a sheet metal original package, a sheet metal member adapted to telescopically, detachably engage the mouth of said original package in place of its original sheet metal lid, a supporting member carried by said sheet metal member and adapted to support said original package and said sheet metal member in an inclined position, and a lid having a flaring-shaped rim hinged to one edge of

said sheet metal member and adapted to open and close the mouth of said original package.

3. A display and vending apparatus comprising in combination with a sheet metal original package and the sheet metal lid of said original package, a first sheet metal band adapted to telescopically, detachably engage the mouth of said original package in place of its original sheet metal lid, a supporting member carried by said first band and adapted to support said original package and said first band in an inclined position, and a second band hinged to said first band and having a flaring-shaped section to form a close joint with said first band and a cylindrical section to be engaged telescopically by the sheet metal lid of said original package to jointly constitute a hinged lid to close the mouth of said original package.

4. A display and vending apparatus comprising in combination with a sheet metal original package and the sheet metal lid of said original package, a first sheet metal band adapted to telescopically detachably engage the mouth of said original package in place of its original sheet metal lid, a supporting member carried by said first band and adapted to support said original package and said first band in an inclined position, and a second band hinged to said first band and forming a close joint therewith, said second band having a cylindrical section to telescopically detachably engage the sheet metal lid of said original package to jointly with said second band constitute a hinged lid for the open mouth of said original package displaying the label on the original box lid.

5. A display and vending apparatus comprising in combination with a sheet metal original package, an annular sheet metal member adapted to telescopically detachably engage the mouth of said original package in place of its original sheet metal lid, a sheet metal supporting member carried by said annular sheet metal member and adapted to support said original package and said annular sheet metal member in an inclined position, and a lid hinged to the upper edge of said annular sheet metal member and adapted to close the mouth of said original package by gravity.

In testimony whereof I have affixed my signature.

EDWARD BRUNHOFF.
